UNITED STATES PATENT OFFICE

109,164

DESIGN FOR A STOVE CABINET

Hjalmer E. Thelen, Wisconsin Rapids, Wis., assignor to Prentiss-Wabers Products Co., Wisconsin Rapids, Wis., a corporation of Wisconsin

Application January 28, 1938, Serial No. 74,621

Term of patent 3½ years

To all whom it may concern:

Be it known that I, Hjalmer E. Thelen, a citizen of the United States, residing at Wisconsin Rapids, in the county of Wood and State of Wisconsin, have invented a new, original, and ornamental Design for a Stove Cabinet, of which the following is a specification, reference being had to the accompanying drawing forming a part thereof.

The figure is a perspective elevational view of a stove cabinet showing my new design.

The side of the stove not shown in the drawing is identical in design with the side shown. The rear of the stove is plain.

I claim:

The ornamental design for a stove cabinet as shown and described.

HJALMER E. THELEN.
